United States Patent Office

Des. 214,588
Patented July 1, 1969

214,588

BLOCK LAYING TOOL

Legrand J. Mercure, 2323 Ridgway Ave.,
Atlanta, Ga. 30318

Filed Apr. 11, 1968, Ser. No. 11,417

Term of patent 14 years

Int. Cl. D8—02

U.S. Cl. D8—45

Fig. 3

Fig. 4

Fig. 5

FIG. 1 is a front-top-side perspective view of a block laying tool embodying my new design, the block aligned therewith representing a conventional block for illustrative purposes only;

FIG. 2 is an end elevational view of the block laying tool shown in FIG. 1;

FIG. 3 is a cross sectional view taken substantially along line 3—3 in FIG. 1;

FIG. 4 is a plan view of the block laying tool shown in FIG. 1; and,

FIG. 5 is a bottom plan view of the block laying tool shown in FIG. 1.

I claim:

The ornamental design for a block laying tool, substantially as shown and described.
